UNITED STATES PATENT OFFICE

JAMES WILLARD HARVEY, OF WINTHROP, MAINE

MOTOR INSTALLATION

Application filed July 13, 1931. Serial No. 550,303.

My invention relates particularly to means for installing what is commonly termed an outboard motor inside of a boat.

One object is to provide a simple and inexpensive construction involving improvements on the invention of my Patent 1,786,997.

A special object is to provide a simplified mounting for the motor in the casing.

Another object is to provide means of construction such that the motor can be readily removed or installed in the casing.

Another object is to provide an improved automatic drain.

Another object is to provide means for draining the boat as well as the casing when the boat is in motion.

Fig. 1 is a longitudinal sectional view of a casing and side elevation of a motor and showing the propeller and its carrying frame retracted in dot and dash lines.

Fig. 2 is a transverse section of a boat on a very small scale showing an installation embodying my invention.

Fig. 3 is an enlarged cross section of the casing showing the drains and engine exhaust.

Fig. 4 is a transverse section of the propeller housing.

Fig. 5 is a plan view of the casing and showing the propeller housing and frame in section.

Fig. 6 is a diagrammatic plan of a modification.

The casing may be formed of suitable material such for instance as cast metal having a side wall 7, a bottom wall or floor 8 and a projecting flange 9 for attachment to the bottom of a boat or the walls might be parts of

the boat structure. The bottom of the casing has an opening 10 in its rear end which is preferably circular and which is normally closed by bottom plate 11. A resilient gasket 12, for instance, of rubber, serves as a yielding support for the bottom plate and attached parts.

The motor 14 may be of any suitable type usually provided with a control handle such as 15, and with the cylinders and fly wheel at the top. The vertical housing 16 contains

the shaft and gear connection to the propeller 17 and supports the motor cylinders and associated parts. The motor may be supplied with cooling water for instance, through a pump 18. The propeller shaft housing may 55 also carry the exhaust passages and have an outlet such as 19. The guard 20 serves to protect the pump and propeller. Features of the housing 16 and its various passages are more fully shown and claimed in my application 582,980, filed December 24, 1931. 60

The motor is supported by a frame of which the bottom plate 11 is a part. The sleeve 21 in which the propeller housing 16 is supported and preferably rotates is secured 65 to the bottom plate in any suitable manner, for instance by a flange 22, which may be riveted, bolted, welded or integral with the bottom plate preferably at its front edge. A bracket or arm 23 has upper and lower 70 branches at its rear end secured for instance by cap screws 24, to the front side of the sleeve 21 at its upper and lower ends respectively. The front end of this bracket is pivotally supported by lugs 25, which may be 75 cast integrally with the bottom and front wall of the casing. The pivots are formed by pins such as 26, which are detachably mounted in the lugs 25 so that they may be readily retracted for disconnecting the arm from the 80 casing. These pins may have finger pieces 27, to facilitate retraction and they may be supported by spring strips 28 for holding them yieldingly and detachably in position. The upper part of the sleeve 21 is preferably split 85 and provided with flanges 30 adapted to be drawn toward each other by a screw 31, so as to vary the frictional resistance of the shaft housing inside the sleeve and thus control the resistance to rotation of the engine and propeller on a vertical axis. The propeller housing has a collar 32, which rests on the upper end of the sleeve 21 to support the weight of the motor and propeller. The length of the bracket 23 is preferably less than the height 90 of the casing 7 so that the motor and the propeller may be tilted about the single axis of the hinge pins 26 in such a manner that the propeller and the lower end of the housing can be retracted within a minimum space. 100

In the bottom of the casing and preferably on opposite sides of the center line of the bottom plate 11, I provide drain outlets 35 and 36 so that the movement of the boat through the water will draw out the water by suction. These drain outlets are preferably on opposite sides of the center line of the casing so as to be free from the exhaust port 19, and thus secure a maximum suction. One of these drain outlets is preferably connected by means of a pipe 37, to the inside of the boat outside of the casing where a screened inlet 38, is provided. This pipe 37 may be a flexible rubber hose secured on to the end of a nipple 39, projecting upwardly from the suction outlet 36.

The motor mounting is so constructed that it may be readily tilted into the dot and dash line of Fig. 1 for the purpose of inspection, repair, or replacement of the propeller. The motor will also automatically be thrown into this position in case the propeller housing or guard strikes an obstacle. When the obstacle strikes the guard 20, the tendency is to swing the propeller housing and motor about the pivot 26, and as soon as the arm 23 is raised at all, the forward inertia of the motor and the upper end of the propeller housing tends to move these parts forwardly so that the reTRACTING action is facilitated by the check-ing of the movement of the boat.

When the motor is dropped down into place the gasket 12 serves as a cushion to prevent shock. This also makes it possible to main-tain a nearly water-tight seat when the boat is in motion.

In this construction the casing 7 is prefer-ably open at the top so that any leakage of gas or oil from the motor, or its supply tank, can fall directly into the casing and not into the boat. When the boat is moving the water in the casing as well as the water out-side of the casing, but inside of the boat, is drawn out through the suction outlets 35 and 36 so as to maintain buoyancy and dryness of the boat and casing.

For transportation purposes it is a very simple and quick matter to detach the entire motor and its supporting frame by simply reTRACTING the pins 26 by one hand.

By locating both of the drains in the bottom of the movable plate, it will be seen that they are both automatically lifted clear of the bottom of the boat when the motor is lifted and the bottom of the boat is thus left clear and free from obstructions.

In the form shown the casing is provided with downwardly projecting longitudinal ribs 40 extending substantially the length of the casing from front to rear on each side. These ribs serve several functions, i. e., rein-forcement to the casing per se, guards to pro-tect the drain outlets, and stabilizing keel sections. These ribs may be cast integral-ly with the casing and while they add very

little to the amount of metal required they materially strengthen the bottom of the cas-ing.

In smaller boats the casing might fill the entire width of the boat, or the rear or other portion of the boat might constitute the cas-ing. In such a case transverse bulkheads 41, 42 might constitute the front and rear walls of the casing, and the sides 43 of the boat or longitudinal bulkheads might constitute the side walls. The motor frame, the sup-porting plates, the drainage and the tilting action would be the same as above described.

I claim:

1. A motor installation for a boat comprising a casing having an opening in the bottom, a motor and propeller unit movable in the casing and having a bottom plate to close said opening, a clamping sleeve member for supporting the motor unit in the casing, an arm rigidly connected to said sleeve member any readily detachable means for pivotally supporting the front end of said arm in the bottom of said casing to permit the quick detachment of the motor unit from the casing. 80

2. A motor installation for a boat comprising a casing having an opening in the bottom, a motor and propeller unit movable in the casing, an arm pivotally mounted in the casing, a sleeve member and bottom plate for supporting the motor unit in the casing, said arm being connected to said sleeve member and spring pressed pins for pivotally sup-porting said arm in said casing to permit the quick detachment of the motor unit from 100 the casing. 90

3. A motor installation for a boat comprising a casing having an opening in the bottom, a motor and propeller unit movable in the casing and having a bottom plate to close 105 said opening, a sleeve member secured to the bottom plate for supporting the motor unit in the casing, an arm bolted to said sleeve member and readily detachable means for pivotally supporting the front end of said 110 arm in the bottom of said casing to permit the quick detachment of the motor unit from the casing.

4. A motor installation for a boat comprising a casing having an opening in its floor, 115 a bottom plate adapted to close said opening, a motor and propeller unit carried by said plate, a hinged arm for tilting said unit, two drains carried by said plate, one of said drains having an opening into the casing and a pipe connected to the other drain with its inlet in the boat outside of the casing.

5. A motor installation for a boat comprising a casing having an opening in its floor, 125 a bottom plate adapted to close said opening, a motor and propeller unit carried by said plate, a hinged arm connected to said unit and to the bottom of the casing, a drain car-ried by said plate and movable therewith and 130

a pipe connected to said drain with its inlet in the boat outside of the casing.

6. A motor installation for a boat comprising a casing having an opening in its floor, a bottom plate adapted to close said opening, a motor and propeller unit carried by said plate, two drains carried by said plate on opposite sides of the center line, one of said drains having an opening into the casing and 10 a pipe connected to the other drain with its inlet in the boat outside of the casing.

7. A motor installation for a boat comprising a casing having an opening in its floor plate, a bottom plate demountably supported 15 in said opening, a motor and propeller unit carried by said bottom plate and having an exhaust outlet beneath said bottom plate and two drain outlets, one arranged on each side of the exhaust outlet and a suction pipe connected to one drain outlet and extending 20 over the edge of the casing into the boat.

8. A motor installation for a boat comprising a casing having an opening in its floor plate, a bottom plate demountably supported 25 in said opening, a motor and propeller unit carried by said bottom plate and having an exhaust outlet beneath said bottom plate and two drain outlets carried by said bottom plate, one arranged on each side of the 30 exhaust outlet.

9. A motor installation for a boat comprising a casing having an opening in its floor plate, a bottom plate demountably supported 35 in said opening, a motor and propeller unit carried by said bottom plate and having an exhaust outlet beneath said bottom plate and two drain outlets, one arranged on each side of the exhaust outlet, one drain outlet having its inlet in the casing and a goose neck pipe 40 connected to the other drain outlet and having an inlet in the boat.

10. A motor boat installation comprising a casing having a floor plate with an opening in its rear end, a power unit supported 45 in the casing and comprising a motor having a propeller housing and a supporting frame, the power unit having a bottom plate carried by the frame for closing the opening in the floor plate, an arm projecting forwardly 50 from the frame and detachably pivoted to the inside of the casing in the front end thereof.

11. A motor installation as set forth in claim 10, having a suction drain outlet extending beneath the casing at one side of the 55 propeller housing.

12. A motor installation for a boat comprising an enclosure having walls surrounding an opening in the bottom of the boat, a motor and propeller unit movable in the enclosure, the cylinders and fly wheel being at the top of the unit and having a bottom plate to close said opening, a clamping sleeve member for supporting the lower part of the motor unit in the enclosure, an arm rigidly 60 connected to said sleeve member and readily

detachable means for pivotally supporting the front end of said arm close to the bottom of said enclosure to permit the quick detachment of the motor unit from the enclosure and to permit the automatic forward tilting 70 of the motor and the lifting of the propeller when meeting an obstruction.

13. A motor installation comprising a casing having a floor plate, a side wall integral therewith, and having an opening in the floor plate, a web connecting the front side wall and the floor plate, a supporting frame having a bottom plate fitting said opening, an arm connected to the front of said frame and having its front end hinged to said web and 75 a power unit carried by and tilting with said frame.

14. A motor boat installation comprising a compartment of the boat constituting a casing having bulkheads forming the side walls 85 of the casing, a floor plate secured in the bottom of the boat and having an opening, a frame hinged to the floor plate in front of the opening and having a bottom plate to close said opening, a power unit carried by 90 said frame having a motor on its upper end and having a propeller beneath the bottom plate.

15. A motor boat installation comprising a casing having two interior lugs, and an 95 opening in rear thereof, a frame having a bottom plate to close said opening and having two arms, hinge pins for connecting said arms to said lugs, means connected to said pins to enable the withdrawal of both pins 100 by one hand and a power unit carried by said frame and tiltable and removable therewith.

16. A motor boat installation comprising a casing having an opening in the bottom, a plate and housing normally supported in and closing said opening, a propeller supported by the housing beneath the plate, a sleeve secured to said plate and surrounding said housing, a collar on the upper end of said housing supported on the upper end of said sleeve below the upper edge of the casing, a bracket having its front end hinged in the front end of the casing at the bottom thereof and having its rear end secured to said sleeve. 110

17. A motor installation comprising a casing secured in the bottom of the boat and having an opening in the bottom of the casing in the rear end thereof, a plate detachably mounted in said opening, a propeller housing secured to said plate at its front edge, 115 a propeller carried by the housing beneath said plate, and a supporting bracket hinged at its front end to the interior of the casing in the front end thereof, the rear end of the bracket having upper and lower arms secured to the propeller housing, the length of the bracket being less than the height of the casing so that the propeller may be retracted through said opening into the casing by merely tilting the housing. 120

18. A motor installation comprising a casing adapted to be mounted in the bottom of a boat and having an opening in the bottom of the casing and a surrounding side wall, a propeller and housing having a detachable bottom plate normally closing said opening, said plate having a drain outlet, and a suction pipe connected to said drain outlet, said suction pipe extending over the side wall of 10 the casing and having a suction inlet in the bottom of the boat outside of the casing for automatically bailing the boat when the plate and propeller are in place in the casing.
19. A motor boat installation comprising 15 a bottom plate having an opening in its rear, a plate and housing normally supported in said opening, a propeller carried by said housing beneath said plate, a sleeve secured to said plate and surrounding a part of the 20 housing, and a bracket having its front end hinged to the bottom plate in front of the opening and having upper and lower branches secured to the upper and lower ends of said sleeve respectively.
20. A motor boat installation comprising a bottom plate having an opening in its rear, a plate and housing normally supported in said opening, a propeller carried by said housing beneath said plate, a sleeve secured to said 25 plate and surrounding a part of the housing, a collar secured to the housing and rotatively supported upon the upper end of said sleeve, and a bracket having its front end hinged to the bottom plate and having upper and 30 lower branches secured to the upper and lower ends of said sleeve respectively.

JAMES WILLARD HARVEY.
